US00D908227S

(12) **United States Design Patent** (10) Patent No.: **US D908,227 S**
Åkerman et al. (45) Date of Patent: ** Jan. 19, 2021

(54) **WOUND DRESSING**

- (71) Applicant: **Mölnlycke Health Care AB**, Gothenburg (SE)
- (72) Inventors: **Julia Åkerman**, Gothenburg (SE); **Robin Long**, Gothenburg (SE); **Maria Gustin Bergström**, Linköping (SE); **Linda Östlund**, Kungsbacka (SE); **Lena Jacobsson**, Gothenburg (SE)
- (73) Assignee: **Mölnlycke Health Care AB**, Gothenburg (SE)

(**) Term: **15 Years**

(21) Appl. No.: **29/683,312**

(22) Filed: **Mar. 12, 2019**

Related U.S. Application Data

(63) Continuation of application No. 29/625,440, filed on Nov. 9, 2017, now abandoned.

(30) **Foreign Application Priority Data**

May 11, 2017 (EM) 003996115

(51) **LOC (13) Cl.** **24-04**

(52) **U.S. Cl.**

USPC **D24/189**
